UNITED STATES PATENT OFFICE.

EDWARD H. McCLOUD, OF COLUMBUS, OHIO, ASSIGNOR TO THE KINNEAR MANUFACTURING COMPANY, OF COLUMBUS, OHIO, A CORPORATION OF OHIO.

DOOR OR SHUTTER.

Application filed May 21, 1921. Serial No. 471,450.

To all whom it may concern:

Be it known that I, EDWARD H. McCLOUD, a citizen of the United States, residing at Columbus, in the county of Franklin and State of Ohio, have invented a certain new and useful Improvement in Doors or Shutters, of which the following is a specification.

The object of this invention is a construction of door or shutter in which the several sections or panels are in balanced relation and simultaneously and easily moved to opening or closing position. With an installation of such a construction as hereinafter contemplated half the closing element may extend exteriorly while the other half extends interiorly of the building. Other objects will appear from the following description.

20 The invention is embodied in the example herein particularly shown and set forth, the features of novelty being finally claimed.

In the accompanying drawings—

Figure 1 is an elevation of one side of the closed door, the other side (not shown) being a symmetrical duplicate except as to the counterweighting apparatus and operating mechanism which appears on the side shown.

30 Fig. 2 is a vertical section on the line II—II Fig. 1 looking to the right.

Fig. 3 is a view like Fig. 2 showing the door opened.

In the views 5 designates the upper panel or door section which is shown as hinged to the building at 6 at the top of the door opening to swing outward when opened. 7 designates the lower panel. The lower corners of the lower panel are provided with laterally projecting stud shafts equipped with rollers 8 like those indicated in Fig. 1 to travel in channels 9 at the opposite sides of the door opening. Hingedly connected to the upper edge of the upper panel or at a point near thereto and the corresponding edge of the lower panel is a bar 10, and hingedly connecting the lower edge of the upper panel and the corresponding edge of the lower panel is a bar 11. The hinging point 12 of the bar 10 with the lower panel, and the hinging point 13 of the bar 11 with the lower edge of the upper panel are each offset in opposite directions from the plane of movement of the lower end of the lower panel between the

channels 9 so that draft upward on the lower panel is easily initiated when the panels are in closed position and therefore lie in the same plane as shown in Fig. 2. In order to permit the desired maximum elevation of the panels the bars 10 and 11 are curved at their ends to reach around the corners of the panels in both the open and closed positions of those members.

Any small opening between the upper and lower panels when in closed position can be covered by a strip 15 secured along the lower edge of the upper panel so as to leave a projecting margin for the purpose stated.

To facilitate the operation of the door, when heavy, chains or other suitable flexible members 17 and 18 are conveniently connected with the opposite stud shafts containing the rollers 8, said flexible members traversing suitable sheaves such as at 19 and 20 on a shaft 21 to a counterweight 16. The sheaves 19 and 20 can be fixed to the shaft 21 and the latter can be driven by means of a spur gear 22 engaged by a pinion on the shaft 23 of a sprocket wheel 24. The sprocket wheel 24 is shown as carrying an endless chain 25 that extends to within easy reach of an operator for turning the shaft 21 in the direction necessary to open or close the door.

The forms and arrangement of parts can be changed without departing from the gist of the invention as claimed.

What I claim is:

1. A closure for a door or window opening including, in combination, an upper closing panel hinged at its upper edge to a fixed point to open at one side only of the opening to be closed, a lower closing panel sliding at its lower end to open at the opposite side only of the opening to be closed, an operating bar hingedly connecting the upper edge of the lower panel to a fixed point near the upper edge of the upper panel, an operating bar hingedly connecting the lower edge of the upper panel to the lower edge of the lower panel, and guiding means for the lower edge of the lower panel.

2. A closure for a door or window opening including, in combination, an upper closing panel hinged at a fixed point at its edge to open at one side only of the opening to be closed, a lower closing panel slid-

ing at its lower end to open at the opposite side only of the opening to be closed, an operating bar hingedly connecting the upper edge of the lower panel to a fixed point near the upper edge of the upper panel, an operating bar hingedly connecting the lower edge of the upper panel to the lower edge of the lower panel, guiding means for the lower edge of the lower panel, 10 the hinging points of said bars with the lower edge of the upper panel and with the upper edge of the lower panel being offset from the plane of movement of the lower edge of the lower panel when the panels 15 are in closed position, said bars being curved to reach around the swinging edges of said panels.

3. A closure for an opening in a building wall comprising top and bottom closure members, said opening being defined in part by side members each having a guideway 20 extending vertically from one end thereof, one of said closure members being pivotally supported to swing with respect to said opening, guide means carried at one end of the other closure member, said guide means extending into and being movable in said guideways, and links connecting the top and bottom ends of one closure member with the like ends of the other closure member.

tom ends of the other member and operating upon the opening or closing swinging 25 movement of one member to impart a like movement to the other member, the pivotal connections of the members relatively approaching and receding from each other during the opening or closing movements 30 respectively.

4. A closure for an opening in a building wall comprising top and bottom closure members, said opening being defined in part by side members each having a guideway 35 extending vertically from one end thereof, one of said closure members being pivotally supported to swing with respect to said opening, guide means carried at one end of the other closure member, said guide 40 means extending into and being movable in said guideways, and links connecting the top and bottom ends of one closure member with the like ends of the other closure member.

EDWARD H. McCLOUD.
